Henry de S. Lauve, Grosse Point, Mich., assignor to Lyon Incorporated, Detroit, Mich., a corporation of Delaware

Filed Feb. 24, 1960, Ser. No. 59,506

Term of patent 14 years

(Cl. D14—30)

Fig. 1

Fig. 2

FIGURE 1 is a side elevational view of a combined tire and tire trim showing my new design; and

FIGURE 2 is a fragmentary sectional perspective view thereof.

The characteristic features of the combined tire and tire trim reside in the tire trim having the openings as shown. The portions of a wheel shown in broken lines are included for illustrative purposes only.

I claim:

The ornamental design for a combined tire and tire trim as shown and described.
